VAPOR DISCHARGE LAMP

Daniel S. Gustin, Bloomfield, N. J., assignor to Westinghouse Electric & Manufacturing Company, East Pittsburgh, Pa., a corporation of Pennsylvania

Application July 3, 1937, Serial No. 151,817

6 Claims. (Cl. 176—122)

This invention relates to discharge lamps wherein an electric discharge occurs between two electrodes in an ionizable medium and has particular reference to a lamp of this type which is self-contained.

In lamps of this character, the life thereof is more or less dependent upon the life of the electrodes. Since the spacing of the electrodes is relatively great thus causing the lamp to have a high resistance, a high voltage would be required to initiate a discharge unless the high voltage is in some manner compensated for. If a high voltage is applied, sufficient to initiate a discharge, the electrode, momentarily functioning as the cathode, will sputter, shortening its useful life and naturally that of the lamp. Also, when the voltage is applied before the cathode reaches a temperature to freely emit electrons, the discharge is usually concentrated at one spot which, due to ion bombardment, overheats such spot again shortening the life of the lamp.

For the purpose of controlling the amount of current supplied to a lamp of this type it has been customary to employ auxiliary starting equipment such as an impedance or the like connected in series with the electrodes of the tube. Inasmuch as such equipment is of a cumbersome nature, the necessity therefor has to a great extent retarded the adaptation of such lamps to domestic lighting for homes and the like.

It is accordingly an object of the present invention to provide a gaseous discharge lamp which is operable directly from the usual source of commercial voltage.

Another object of the present invention is the provision of a gaseous discharge lamp requiring no cumbersome auxiliary equipment to initiate a discharge.

Another object of the present invention is the provision of a gaseous discharge lamp provided with internal means for limiting the current supplied to the lamp and which at the same time heats the electrodes to an electron emitting temperature.

A further object of the present invention is the provision of a self-contained gaseous discharge lamp having an impedance forming an integral part of the lamp serving to limit the current and at the same time being operable to heat the electrodes to an electron-emitting temperature, and, in addition, such self-contained lamp is provided with an internal device for initially ionizing the gas within the envelope and causing a discharge between the operating electrodes.

Still further objects of the present invention

will become obvious to those skilled in the art by reference to the accompanying drawing wherein:

Figure 1 is a side elevational view of a discharge lamp constructed in accordance with the present invention,

Fig. 2 is a cross-sectional view on an enlarged scale of either electrode end of the tube since both are identical,

Fig. 3 is a cross-sectional view taken on the line III—III of Fig. 1,

Fig. 4 is a cross-sectional view showing a modification of construction which the electrode end of the tube may take, and

Fig. 5 is an elevational view of a portion of the modified construction shown in Fig. 4.

Referring now to the several figures in detail, the lamp shown in Fig. 1 may comprise a vitreous envelope 5 which, after evacuation, is filled with a metallic vaporizable material, such as mercury, sodium, or the like, or a gaseous environment such as helium, hydrogen, neon, argon, or the like, either alone or in combination with the metallic vaporizable material.

As shown in Figs. 1, 2, and 3, the ends of the tubular envelope may be closed by a metallic closure member 6, of suitable alloy steel and sealed to the envelope to form a vacuum-tight connection, such as by a feather edge 7, if desired, although this is not essential, and having a cylindrical portion 8 closed at one end and forming re-entrant stems for the lamp.

An electrode 9 of refractory metal, such as tungsten, which may be coated with an electron-emitting material, as is well known in the art, has one of its ends welded or otherwise affixed to the metallic reentrant portion 8 while its remaining end is similarly secured to a metallic collar or the like 10. This metallic collar is suitably insulated from the reentrant stem 8 by an insulating collar 12 and supports a bi-metallic thermostatic strip 13 (see Fig. 3) as well as an insulated conductor 14 extending internally of the envelope which initially interconnects the electrodes. Contact is established with the conductor 14 by a projection 15 on the bi-metallic strip 13 engaging an exposed portion of the conductor 14 at each end, as can be seen in Figs. 1 and 2.

For the purpose of heating the electrodes 9 to an electron-emitting temperature, as well as to heat the bi-metallic strips 13 and at the same time limit the amount of current supplied to the lamp, an impedance, such as a resistance 16, is provided which forms an integral part of the lamp. Since such resistance element is disposed at each end

of the lamp, a detailed description of only one should suffice.

Referring more particularly to Figs. 1, 2, and 3, the resistance element 16 comprises a core of insulating material 17 upon which is disposed a winding 18 to give the desired ohmic resistance. For the purpose of centering the resistance element 16 relative to the reentrant stem portion 8, a pair of spacers 19, having an overall diameter approximately equal to the internal diameter of the reentrant stem, surrounds the resistance element. In order to connect this resistance element in series with the electrode and the source of electrical energy L1, L2, one end of the winding 18 is connected to the metallic reentrant stem 8 through the medium of a conductor 20 which extends upwardly of the reentrant stem and is secured near the base by welding or soldering to facilitate assembly.

Each end of the lamp may be provided with an insulated base 22 cemented to the envelope and having a metallic thimble 23 crimped around an annular projecting portion of the base 22. To complete the circuit from the source through the resistance element to the electrode, the remaining end of the resistance is connected by a conductor 24 which is soldered or otherwise affixed to the metallic thimble 23.

When current is supplied to the lamp, it passes through the thimble 23 and conductor 24 to the winding 18 and thence through reentrant stem 8 to electrode 9, metallic collar 19, bi-metallic strip 13, and conductor 14 to the other electrode, thus connecting both resistances, bi-metallic strip, and electrodes in series with the source L1, L2. The passage of current accordingly causes the resistance element 16 to heat up and heat the electrode 9 to electron emitting temperature, as well as the bi-metallic strip 13. Upon the thermostatic strip 13 being heated to an appropriate temperature, it will flex in the manner shown in full lines in Figs. 1 and 2, thus breaking the connection between the tip 15 and the conductor 14.

Despite the fact that current is flowing simultaneously through both resistance elements and they heat the respective juxtaposed thermostatic elements, it is nearly impossible to have both thermostatic elements break their connection at precisely the same instant. Accordingly, upon the opening of the thermostatic strip 13, an arc will first be initiated between the exposed portion of the conductor 14 and the electrode 9 functioning as cathode. This will initially ionize the gas within the lamp, thus facilitating the striking of an arc between the electrodes 9 when the other bi-metallic strip opens.

After the opening of both thermostats 13, current flows entirely through the resulting arc since the conductor 14 is completely opened at both ends. The current supplied to the lamp, however, is limited by the integral resistance elements 16, both of which remain permanently connected in series with the electrodes. Accordingly, the resistance elements may be made any desired value so as to give the lamp a preselected wattage. For example, the lamp may be designed to operate on 120 volts at a total of 25 watts, and each resistance given a value such as to consume 5 watts of energy, leaving a total of 15 watts for light emission, or any other desired proportion.

In Figs. 4 and 5, a modification of the device is shown wherein the resistance elements 16, although in operation forming an integral part of

the lamp, may be removed for replacement or repair. To this end the metallic reentrant stem portion 8 is provided with coarse threads or the like 25 and the seal 7 is of smaller diameter and is sealed to a small annular portion 26 formed on 5 a closure member 27. This closure member may then be fused at 28 to the tubular portion of the envelope 5 to facilitate assembly of the parts.

The base in this instance may consist of an insulating collar portion 29 of sufficient diameter 10 to surround the annular portion 26 and the metallic thimble 23, both of which are rigidly secured to the core 17 of the resistance element 16. The conductor 24 extends through a bore 30 provided in the core and again connects to one 15 end of the winding 18 while the other end of the winding 18 is connected to a metallic shell 32 rigidly secured to the core 17 which is provided with threads of the same diameter and pitch, as that of the metallic reentrant stem portion 20. 25. In all other respects the construction and elements, such as the electrodes and thermostats, are identical to the modification previously described.

The removable resistance element prior to its 25 integral connection to the lamp is shown in Fig. 5. To assemble, it is only necessary to insert the core 17 within the metallic reentrant stem 8 and rotate the unit. The metallic shell 32 rigidly secured to the core 17 then threadably engages the 30 portion 25, drawing the unit downwardly of the reentrant stem until the insulating collar portion 29 of the base snugly surrounds the small annular portion 26.

Inasmuch as the winding 18 is connected to the 35 thimble 23 and the shell 32, the engagement of the unit with the reentrant portion 8 immediately completes an electrical connection to the electrode 9 and to the bi-metallic strip 13. Also, since the reentrant portion is sealed to the closure member 27 which in turn is fused to the remainder of the envelope 5, removal of the resistance unit in no way disturbs the pressure of the gas within the lamp.

It will thus be readily appreciated by those 45 skilled in the art that the invention pertains to a discharge lamp wherein an integral resistance element is provided which limits the current supplied to the lamp so that it may be operated directly from electrical supply sources of the 50 usual commercial voltage without the necessity for cumbersome auxiliary equipment. Moreover, the resistance element also functions as a heater for the purpose of initially heating the electrodes to an electron-emitting temperature, and at the same time serves to cause operation of a thermostatic element for breaking the circuit and initiating the arc.

Although two modifications of the invention have been shown and described, it is to be understood that other embodiments thereof may be made without departing from the spirit and scope of the appended claims.

I claim:

1. A gaseous discharge lamp comprising a 65 vitreous envelope provided with at least one reentrant stem, said stem having a portion thereof of heat conducting material, an ionizable medium within said envelope, electrodes within said envelope adapted to sustain an arc therebetween 70 during operation of said lamp, and means disposed interiorly of said reentrant stem and electrically connected to at least one of said electrodes, said means being disposed in close proximity to said heat conducting portion of said 75

reentrant stem and to said electrode and constituting a heater for heating said electrode to an electron emitting temperature to facilitate the initiation of said discharge and said means being operable to limit the current supplied to said lamp during continuance of said discharge.

2. A gaseous discharge lamp comprising a vitreous envelope provided with at least one reentrant stem having a metallic portion, an ionizable medium within said envelope, electrodes within said envelope adapted to sustain an arc therebetween during operation of said lamp, and means disposed interiorly of said reentrant stem in contact with the metallic portion thereof and in juxtaposition to at least one of said electrodes for heating said electrode to an electron-emitting temperature and for limiting the current supplied to said lamp during operation.

3. A gaseous discharge lamp comprising a vitreous envelope provided with at least one reentrant stem and containing an ionizable medium therein, electrodes within said envelope adapted to sustain an arc therebetween during operation of said lamp, heat responsive means disposed interiorly of said lamp adjacent said reentrant stem and operable to initially cause ionization of said medium to facilitate the starting of the discharge between said electrodes, and means disposed interiorly of at least one of said reentrant stems in juxtaposition to said heat responsive means and one electrode for heating said electrode to an electron-emitting temperature as well as heating said heat-responsive means, to cause the formation of an arc within said lamp, and for limiting the electrical current supplied to said lamp during operation.

4. A gaseous discharge lamp comprising a vitreous envelope provided with at least one reentrant stem and containing an ionizable me-

dium therein, electrodes within said envelope adapted to sustain an arc therebetween during operation of said lamp, and detachable means adapted to be rigidly secured to said envelope interiorly of said reentrant stem and electrically connected to said electrode, and said means being operable to heat at least one of said electrodes to an electron-emitting temperature and to limit the current supplied to said lamp during operation.

5. A gaseous discharge lamp comprising a vitreous envelope provided with at least one reentrant stem and containing an ionizable medium therein, electrodes within said envelope adapted to sustain an arc therebetween during operation of said lamp, heat responsive means disposed interiorly of said lamp adjacent said reentrant stem and operable to initially cause ionization of said medium to facilitate the starting of a discharge between said electrodes, and detachable means rigidly secured to said envelope interiorly of said reentrant stem and operable to heat at least one of said electrodes to an electron-emitting temperature and to limit the current supplied to said lamp during operation.

6. A gaseous discharge lamp comprising a vitreous envelope provided with at least one reentrant stem and containing an ionizable medium therein, electrodes within said envelope adapted to sustain an arc therebetween during operation of said lamp, and a detachable base for said lamp including an electrode terminal and an integral resistance element adapted to be positioned interiorly of said reentrant stem and electrically connected to at least one of said electrodes for heating said electrode to an electron-emitting temperature, and for limiting the current supplied to said lamp during operation.
